United States Patent Office.

GEORGE KING AND LYNDHURST T. SHOPE, OF FREDERICK CITY, MARYLAND.

Letters Patent No. 81,790, dated September 1, 1868.

IMPROVEMENT IN SEEDING-MACHINES.

The Schedule referred to in these Letters Patent and making part of the same.

TO ALL WHOM IT MAY CONCERN:

Be it known that we, GEORGE KING and LYNDHURST T. SHOPE, of Frederick City, in the county of Frederick, and State of Maryland, have invented certain new and useful Improvements in Metallic Spouts for Seed-Drills; and we do hereby declare that the following is a full, clear, and exact description thereof, reference being had to the accompanying drawings, and to the letters of reference marked thereon, which form a part of this specification, in which—

Figure 1 represents an end view of our seeder, and

Figure 2 is a side view of the same.

The nature of our invention consists in the employment of certain devices, combined and arranged substantially in the manner hereinafter set forth.

To enable others skilled in the art to make and use our invention, we will now describe its construction and operation.

In the accompanying drawings, A represents the seed-box, and B the wheels. C is the axle, and D the frame, upon the side-pieces of which the seed-box is designed to rest. e designates a series of short tubes, having flanges at their upper ends, which are securely fastened to the bottom of seed-box A. d represents a succession of tubes, intended to convey the grain from e into the lower tubes, F and F', to which the shovels i are attached. The upper tube, d, in each series is made sufficiently large to fit loosely over the lower end of tube e, to which it is pivoted, so as to play with a forward and backward motion. The second tube d is made to embrace the lower end of the one above it, and is pivoted in a similar manner. Any number of tubes may be added, always observing the same method of construction. h represents a series of metal braces, two of which are pivoted to projections on F and F', and R and M. The outer ends of braces h are penetrated by the rod f, on which they can play with a vertical motion. k represents a number of pendants, consisting of metal plates, fastened at top to the front of frame D, and bent over at bottom, so as to form an eye, through which rod f is made to pass. m represents a metal rod, bent at right angles near each end, and then bent outwards, to enter the opposite side-pieces of frame A. To this rod, cords are fastened, one of which will connect the rod f with each of the tubes, F F' and R M. When it is desired to lift said tubes entirely out of ground, the rod m will be pushed back against the seed-box, and will be held there by spring s. When it is desired to keep the tubes F and F', together with tubes R and M, in a given position, a pin, j, will be thrust over the top of the braces attached to each of the lower tubes, and through one of the holes made in the projections attached to each of said tubes. By this arrangement, the plows i will be in condition to perform their office.

It will be observed that the tubes conveying the grain to F and F', being pivoted in the manner above described, will have all the desired flexibility of leather or rubber, and, at the same time, possess greater strength and durability.

The above-described tubes may be modified in two ways: The first modification is exhibited by the tubes, which convey the grain into the tube R, in which the second tube, u, is hinged to e at top, and sheathed in tube w, and w sheathed in tube v, which is hinged to tube R. In the second modification, marked M, the tube d' will be hinged at top to e, and sheathed in tube p, which is hinged to M.

We are aware that making seed-spouts in sections, allowing one section to enter the other, and suspending them by a flexible material, is not new. We do not claim, therefore, this feature; but

What we do claim, and desire to secure by Letters Patent, is—

Hinging the lower section of the seed-spouts P V to the tubes or spouts R M, as and for the purpose specified.

In testimony that we claim the foregoing as our own, we affix our signatures in presence of two witnesses.

GEORGE KING,
LYNDHURST T. SHOPE.
